CLAIM

The ornamental design for a tripod, as shown and described.

DESCRIPTION

Fig. 1.1 is a front view of the tripod;

Fig. 1.2 is a rear view of the tripod;

Fig. 1.3 is a right-side view of the tripod;

Fig. 1.4 is a left-side view of the tripod;

Fig. 1.5 is a top view of the tripod;

Fig. 1.6 is a bottom view of the tripod; and

Fig. 1.7 is a perspective view of the tripod.

The portions of the tripod shown in broken lines form no part of the claimed design.
